UNITED STATES PATENT OFFICE.

HOWARD BROOKS, OF WHEATON, ILLINOIS, ASSIGNOR OF TWO-THIRDS TO
GEORGE W. BROWN AND JOHN C. MASTICK, OF WHEATON, ILLINOIS.

PROTECTOR FOR THIRD RAILS OF ELECTRIC RAILWAYS.

SPECIFICATION forming part of Letters Patent No. 714,446, dated November 25, 1902.

Application filed June 23, 1902. Serial No. 112,809. (No model.)

To all whom it may concern:

Be it known that I, HOWARD BROOKS, a citizen of the United States, residing at Wheaton, in the county of DuPage and State of Illinois, 5 have invented a certain new and useful Improvement in Protectors for Third Rails of Electric Railways, of which the following is a specification.

It is the practice to leave the third rail exposed, and owing to the powerful current employed the exposure of the third rail renders the use of such rail dangerous in the event of contact therewith, and if bridged by a conductor of electricity the current is liable to be 10 shunted or short-circuited or other damage created. It is therefore very desirable to guard and protect the third rail, without, however, affecting the transmission of the current or impairing the utility of the rail. 15 The objects of this invention are to construct a simple, efficient, and reliable guard or protector for a third rail by the use of which danger from accidental contact with the rail is reduced to a minimum and the 20 liability of moisture affecting the rail as to its transmission qualities is obviated to the greatest extent possible; to incase or cover the third rail on all sides except the contact side for the trolley with a protector or guard 25 made of material which is a non-conductor of electricity and which will be impervious to and shed water or moisture and which to the greatest extent possible will prevent water and moisture from obtaining access to the 30 rail; to construct a divided or two-part guard or protector for a third rail consisting of sections of suitable non-conducting material with overlapping ends for the sections of the upper division or half of the guard or protector; 35 to furnish a divided sectional guard or protector for a third rail, the sections of the upper and lower portions of the guard or protector breaking joints; to protect the corners of the lower division or half of the guard or 40 protector from being fractured or broken accidentally; to locate and support the third rail and its guard or protector in close proximity to the track-rail without increasing the liability of bridging or spanning the third 45 rail and the track-rail by a conductor of electricity, which would affect the transmission of

the current through the third rail, and to improve generally the construction of the guard or protector and the means for inclosing the third rail in the guard or protector and attaching the assembled parts in position for the third rail to be operative. 55

The invention consists in the features of construction and combinations of parts hereinafter described and claimed. 60

In the drawings, Figure 1 is a side elevation of a portion of a third rail with the guard or protector therefor and showing also the chairs for supporting the parts in position; Fig. 2, a cross-section through the third rail and its guard or protector, showing the end of the lower division or half of the guard or protector in elevation and showing the chair and the tie in elevation, with the track-rail in section; Fig. 3, a detail of the chair, showing the web or fin between the base and the top plate or support in section. 65 70

The third rail A in the construction shown is in the form of a channel-iron having a base a, a top flange a', and a bottom flange a'', the base a furnishing the contact for the trolley wheel or shoe. The third rail is inclosed in a guard or protector consisting, as shown, of an upper division or half and a lower division or half. The guard or protector can be made 75 of burnt clay, concrete, or other suitable material having non-conductive qualities and capable of being formed into shape to be applied to the third rail and furnish a guard or protector on all sides except on the open side, 80 where the trolley enters. The upper division or half B of the guard or protector is made in sections of any suitable length. Each section has a projected rim b, a body b', a depending rim b'', and a flange b'', extending 85 from the lower end of the depending rim. The body b' fits over the outer face of the upper flange a' of the third rail for the projected rim to hang forwardly and downwardly beyond the edge of the upper flange a', so as 90 to form a shed at the top over the third rail, and the depending rim b'' extends part way down on the rear face of the base a of the third rail, so that when a section is in place the upper flange and a portion of the base on 95 the exterior face will be encompassed by the upper division or half of the guard or pro- 100

tector. Each section B of the upper division or half of the guard or protector has an enlarged end B', into which is entered the end of the adjoining section, so that the enlarged end overlies the end of the adjoining section at the juncture between the two sections and forms a stop against the ready entrance of water and moisture between the ends of the adjoining sections. The lower division or half C of the guard or protector is made of sections of the same length as the sections B of the upper division of the guard or protector. Each section has a front or inner ridge or rib c, a body c', and an upwardly-extending rim c², terminating in a curved end face to enter a concave face in the end of the depending rim b² of each section B and having extending out from the rim c² a flange c³, coinciding with the flange b³ when the two divisions or halves are placed or brought together, with the upper division or half B on the lower division or half, as shown in Figs. 1 and 2. The ridge or rib c abuts against the end of the lower flange a² of the third rail, and the body c' abuts against the under face of the lower flange, and the rim c² extends partly upon the base a of the third rail, against the exterior face thereof, so that when the third rail is in place its lower side is supported and covered on the exterior by the lower division or half of the guard or protector, and its upper side is covered or supported by the upper division or half of the guard or protector, inclosing the third rail within its guard or protector on all sides except at the open front, as shown in Fig. 2.

The upper and lower divisions or halves when in place around the third rail are held in position by bolts D, the stems d of which pass through suitable holes therefor in the flanges b³ and c³, and the bolts are held, as shown, by spring-keys d' passing through the projecting end of the stem below the face of the flange c³ of the lower division or half of the guard or protector, or the bolts can be held in any other suitable manner, the spring-keys furnishing, however, a ready means for releasing the bolts to be withdrawn. The outer corner of the lower division or half of the guard or protector, at the front side thereof, is protected against accidental injury from blows or otherwise by an angle-iron E, one flange e of which abuts against the front face of the ridge or rib c and the other flange e' of which abuts against the under face c' in line with the ridge or rib, and the under corner at the rear side of the lower division or half of the guard or protector is also protected against accidental injury from blows or otherwise by an angle-iron E, the flanges e and e' of which abut against the corner faces of the lower division or half of the guard or protector. The upper and lower divisions or halves of the guard or protector are arranged for their sections to break joints, as shown in Fig. 1, and the angle-iron corners of the lower division or half of the guard or protector may

be continuous, so as to furnish a support for the corners as well as a protection therefor.

The third rail and the guard or protector surrounding the third rail are supported in chairs located at suitable distances apart and attached to the ends of the track-ties. The chairs shown each have a receiver F, formed of a bottom plate f and end flanges f', into which the lower division or half of the guard or protector with the angle-irons at its corners are entered, so as to support the third rail and its guard or protector by the lower division or half of the guard or protector resting on the receiver F, as shown in Fig. 2. The receiver is mounted on a web F', consisting of wings f², standing in right-angle relation to each other and extending from a bottom plate F², having holes therein for the passage of bolts f³ or other suitable means for securing the chair as a whole to the end of a tie by the bottom plate and have the chair support the third rail and its guard or protector at the proper plane for the admission of the trolley into the open side of the third rail and its guard or protector. The third rail and its guard or protector are attached, as shown in Fig. 1, to the ends of track-ties G, with intermediate track-ties G' between the ties G for the chairs, and on the track-ties G and G' are secured the track-rails H in any usual and well-known manner. The third rail and its guard or protector are located in proper relation to the track-rail for the trolley on the car running on the track-rails to enter the open side of the third rail to engage with the base a of the third rail for taking up the current in the usual manner. The body c' of each section of the lower division or half of the guard or protector can be provided with holes g for allowing the escape of any water that may enter between the lower flange a² of the third rail and the body c' of the lower division or half of the protector.

The chairs can be affixed to the ends of their ties at regular distances apart for the reception of the third rail and its guard or protector. The angle-iron corners for protecting the under edges of the lower division or half of the guard or protector can be set in position, and the sections of the lower division or half can be slipped or entered into position beneath the third rail, contacting the lower flange and part of the base on the outer face. The sections of the upper division or half of the guard or protector can be slipped or entered into place on the sections of the lower division or half of the guard or protector, so as to break joints with the sections of the lower division or half and with the end of one section of the upper division or half of the guard or protector entered beneath the overhanging cap or enlarged end of the adjacent section, as shown in Fig. 1, with the inner face of the upper division or half of the guard or protector contacting the upper flange and a part of the base of the third rail on the outer face. The two divisions or halves of the

guard or protector are held together against displacement by the stems of the bolts D passing through the adjoining flanges b³ and c³ of the respective divisions or halves of the 5 guard or protector, completing the incasement of the third rail within the guard or protector and leaving an opening at the front side for the admission of the trolley.

It will be seen that when inclosed by the 10 guard or protector the third rail is covered on all sides except the front with a guard or protector of a nature to insulate the third rail against contact therewith, and the guard or protector is of a nature to prevent the admission 15 of sleet or moisture to the contact-face of the third rail to an extent that would interfere with the proper operation of the trolley on the third rail. The guard or protector also serves as a shed against the admission of water or moisture to an injurious degree, and by means of the openings in the body of the lower division or half of the guard or protector any accumulation of water or moisture 20 will be prevented, as the water or moisture is free to escape through the holes. The guard or protector, made of non-conductive material, is a preventive against placing anything of a conductive nature to span or bridge the 25 third rail and the track-rail by which the current would be deflected, shunted, or short-circuited. The guard or protector can be readily and quickly placed in position, and in case of a breakage of a section of either the upper or lower division or half such section 30 can be easily removed and replaced by a whole section, it only being necessary to withdraw the tie-bolts, remove the broken section, insert a new section, and replace the tie-bolts. The guard or protector also enables the third 35 rail to be located much closer to the track-rail than can be done without the guard or protector, as the guard or protector prevents any accidental spanning or bridging of the space between the third rail and the track-rail to 40 interfere with the transmission of the current through the third rail. The guard or protector is a safeguard against contact with the third rail by man or beast, thereby insuring safety against injury or death from contact with the third rail. The guard or protector is simple in construction, can be readily 45 and quickly applied, is easily repaired, and furnishes a cover for a third rail which insures against accidents, all of which features are of utility and advantage in the use 50 of third rails for transmitting an electric current.

The channel-iron formation of the third rail by its upper and lower flanges furnishes 55 a guide for the trolley to run on the base of the rail without danger of side movement to displace the trolley from its contact with the base of the rail. The base or contact face of the rail is set inwardly, so as to leave a space at the 60 front, which prevents rain and sleet from entering to interfere with the contact between the trolley and the rail, and an additional safe-

guard against the admission of rain and sleet is the downwardly and forwardly extending rim of the upper division or half of the guard or 70 protector, which forms a shed under which the rain and sleet cannot readily pass. The guard or protector, while shown in connection with a third rail of channel-iron formation, can be applied to and used with rails of other formation so long as the form of the rail is one to enable the guard or protector to be placed thereover and secured in position as a covering, the acting face of the rail being within the guard or protector, and the guard or 80 protector can be changed to suit the requirements of the rail so long as it is capable of inclosing the rail against contact therewith except by the trolley. The guard or protector by enabling the third rail to be placed closer 85 to the track-rail allows ties of a uniform length to be used, thus avoiding extra-length ties for supporting the third rail and making a saving in the cost of ties.

What I regard as new, and desire to secure 90 by Letters Patent, is—

1. In a guard or protector for third rails, the combination of a detachable sectional upper division or half consisting of an overhanging rim, a main body and a depending 95 rim with a lateral flange and made of non-conductive material, a detachable sectional lower division or half consisting of a front ridge or rib, a main body and an upwardly-extending rim with a lateral flange and made 100 of non-conductive material, and tie-bolts passing through the lateral flanges of the upper and lower divisions or halves of the guard or protector, substantially as described.

2. In a guard or protector for third rails, 105 the combination of a detachable sectional upper division or half consisting of an overhanging rim, a main body and a depending rim with a lateral flange and made of non-conductive material, a detachable sectional 110 lower division or half consisting of a front ridge or rib, a main body having holes therein and an upwardly-extending rim with a lateral flange and made of non-conductive material, and tie-bolts passing through the lateral flanges of the upper and lower divisions 115 or halves of the guard or protector, substantially as described.

3. In a guard or protector for third rails, the combination of a detachable sectional upper division or half consisting of an overhanging rim, a main body and a depending 120 rim with a lateral flange and made of non-conductive material and each section having at one end an enlargement or flange for receiving the end of the adjoining section, a detachable sectional lower division or half consisting of a front ridge or rib, a main body and an upwardly-extending rim with a lateral flange and made of non-conductive material, and tie-bolts passing through the lateral flanges of the upper and lower divisions or 125 halves of the guard or protector, substantially as described.

4. In a guard or protector for third rails, the combination of a detachable sectional upper division or half consisting of an overhanging rim, a main body and a depending rim with a lateral flange and made of non-conductive material, a detachable sectional lower division or half consisting of a front ridge or rib, a main body and an upwardly-extending rim with a lateral flange and made of non-conductive material, tie-bolts passing through the lateral flanges of the upper and lower divisions or halves of the guard or protector, and angle-irons for the under corners of the lower division or half, substantially as described. 15
5. In a guard or protector for third rails, the combination of a detachable sectional upper division or half consisting of an overhanging rim, a main body and a depending rim with a lateral flange and made of non-conductive material, a detachable sectional lower division or half consisting of a front ridge or rib, a main body and an upwardly-extending rim with a lateral flange and made of non-conductive material, tie-bolts passing through the lateral flanges of the upper and lower divisions or halves of the guard or protector, and angle-irons for the under corners of the lower division or half, substantially as described. 20
6. In a guard or protector for third rails, the combination of a third rail of channel-iron formation in cross-section, a divided guard or protector comprising an upper detachable sectional division or half and a lower detachable sectional division or half, the upper division or half consisting of an overhanging rim, a main body and a depending rim with a lateral flange and the lower division or half consisting of a front ridge or rib, a main body and an upwardly-extending rim with a lateral flange, both divisions or halves made of non-conductive material, and tie-bolts passing through the lateral flanges of the upper and lower divisions or halves of the guard or protector for retaining the two divisions or halves in position to inclose the rail on the top, bottom and rear side leaving the front side open for the admission of the trolley to contact the inner face of the base of the channel-iron third rail, substantially as described. 25 30 35 40 45 50
